DESIGN FOR A DESK THERMOMETER

Carl L. Rizer, Springfield, Ohio, assignor to The Ohio Thermometer Company, Springfield,
Ohio, a corporation of Ohio

Application March 9, 1937, Serial No. 68,081

Term of patent 7 years

To all whom it may concern:

Be it known that I, Carl L. Rizer, a citizen of the United States, residing at Springfield, in the county of Clark and State of Ohio, have invented a new, original, and ornamental Design for a Desk Thermometer, of which the following is a specification, reference being had to the accompanying drawing, forming part thereof.

Fig. 1 is a top plan view, Fig. 2, a front elevation and Fig. 3, a side elevation of a desk thermometer, showing my new design.

I claim:

The ornamental design for a desk thermometer, as shown.

CARL L. RIZER.
